UNITED STATES PATENT OFFICE.

JAMES JOLLY, OF BOLTON, ENGLAND.

OPENER FOR COTTON AND OTHER FIBERS.

Application filed November 8, 1924, Serial No. 748,657, and in Great Britain October 2, 1924.

This invention relates to apparatus for opening or separating raw fibrous material such as cotton, wool or the like known as hopper bale breakers or openers, or other machines for similar purposes.

These machines usually embody a hopper to receive the raw fibers, an inclined travelling spiked lattice to pick up the fibers from the hopper, a rotary evener roll to remove 10 and throw back into the hopper unopened tufts of fibers from the spikes of the lattice, and a rotary clearer roll to clear the fibers from the spikes and throw them forward.

According to this invention I provide the 15 machine with additional sets of spiked apparatus between the spikes of which the fibers will be passed and which will further separate and open the fibers before delivery from the machine.

The invention will be fully described with 20 reference to the accompanying drawings.

Fig. 1 is a sectional side elevation of one embodiment of the invention.

Fig. 2 is a sectional side elevation of another embodiment of the invention.

Fig. 3. is a detail view of the adjusting frame for one of the additional spiked lattices.

Fig. 4 is a transverse section of Fig. 3.

The apparatus comprises a hopper or receptacle A, a spiked feed lattice B, a rotary spiked roller C to even or regulate the amount of fiber carried forward on the spikes a of the lattice, and a clearer roller 30 D to remove or deliver forward the fiber from the spikes a, all of which are of ordinary or known construction and disposition.

According to the invention at the delivery side of the spiked lattice A and clearer rollers C and D a second travelling spiked lattice E is mounted which operates in conjunction with moving or fixed spikes F in close proximity to the spikes E. The fibers are passed between the spikes F and E which 45 operate upon the fibers to open any large tufts that have been fed forward by the feed lattice.

In the form of the invention shown in Fig. 1, the additional spiked apparatus comprises 50 a travelling spiked lattice E and a travelling spiked lattice F, both preferably travelling in the same direction to deliver the fiber, the lattice F travelling at a slower speed, though it may be stationary or may even travel in the reverse direction to the lattice E.

The spikes e of the lattice E are set to carry the fiber forward and the spikes f of the lattice F are set to carry the fiber in the reverse direction in order to straighten out or disentangle any lumps of fiber carried forward by the lattice E. The lattices E and F are preferably set horizontal, though if found convenient may be inclined, and the rollers G over which the lattice F travels may be mounted in adjustable bearings g so 60 that the distance between the two lattices may be altered as required for different grades or types of fiber. The lattice E may be mounted in a frame H at each side of the apparatus, as shown in Fig. 3. A clearer roller K takes the fibers from the spikes e of the lattice E and delivers them down a chute L or on to a travelling band.

In the form of the invention shown in Fig. 2 the additional spiked apparatus comprises an extension M of the original inclined spiked lattice B' around an extra roller or carrier m presenting a horizontal or inclined surface E¹ after passing the first evener roll C and a second adjustable spiked 70 travelling lattice F' applied thereto and preferably travelling more slowly in the same direction. An adjustable slide N may be placed under the extended part of the lattice to keep it from sagging and the bottom bearing m¹ may be adjustable to keep the lattice taut. A clearer roller K¹ takes the fibers from the spikes m² of the lattice M and delivers them down a chute L¹ or on to a travelling band.

What I claim as my invention and desire to protect by Letters Patent is:—

1. In a machine for opening cotton or other fibers, the combination with an upwardly extending travelling lattice and an evener roll associated therewith, of an auxiliary spiked apparatus comprising a second spiked lattice to forwardly carry the fiber, means over which a stretch of said second lattice moves and by which it is supported, and a third lattice associated with and movable in proximity to the supported stretch of said second lattice and having spikes set in a direction opposite to the spikes of the second lattice to straighten out lumps of fiber, means for moving said third lattice toward and away from the supported stretch of said second lattice to vary the distance between said second and third lattices, and a clearer roller to remove the 100 105 110

fibers from the spikes of said second and third lattices and deliver said fibers in a forward direction.

2. A machine for opening cotton and other fibers comprising a hopper to receive the fibers, an upwardly projecting, traveling, spiked lattice to lift the fibers from the hopper, an evener roll associated with said lattice to prevent large lumps of fiber being carried forwardly, a clearer roll to remove the fibers from a portion of the spiked lattice, an auxiliary spiked lattice to which the fibers are delivered and having another lattice in close cooperating proximity thereto and movable towards and from the same to

vary the distance between the spikes of the two latter lattices, the spikes of the lattices being set in opposite directions to straighten out lumps of fiber, the lattice operating in proximity to the auxiliary spiked lattice being movable relatively to the said auxiliary lattice and at a slower speed than the latter to straighten out and even the fibers, and a clearer roller to remove the fibers from the spikes of the auxiliary lattice and the lattice in proximity thereto and deliver the fibers in a forward direction. 20 25

In testimony whereof I have hereunto set my hand.

JAMES JOLLY.
